F. R. BLANKENAGEL.
SAFETY DEVICE FOR WINDOWS.
APPLICATION FILED OCT. 22, 1918.

1,325,227.

Patented Dec. 16, 1919.

UNITED STATES PATENT OFFICE.

FRANZ RICHARD BLANKENNAGEL, OF PASSAIC, NEW JERSEY.

SAFETY DEVICE FOR WINDOWS.

1,325,227.

Specification of Letters Patent.

Patented Dec. 16, 1919.

Application filed October 22, 1918. Serial No. 259,224.

To all whom it may concern:

Be it known that I, FRANZ RICHARD BLANKENNAGEL, a citizen of the United States, residing at Passaic, county of Passaic, and State of New Jersey, have invented certain new and useful Improvements in Safety Devices for Windows, of which the following is a specification.

This invention relates to improvements in 10 safety devices for windows, and has as its principal object the provision of means whereby a person is prevented from accidentally falling out of the window opening, when leaning outward therefrom, as in the 15 process of cleaning.

A further object is to provide such devices in forms which may be readily engaged or disengaged from the window frame and which present no impediment to the use or 20 operation of the window.

A still further object is to produce devices in forms which may be cheaply manufactured and placed in position without difficulty.

25 These and other like objects are attained by the novel construction and combination of parts hereinafter described and shown in the accompanying drawings, forming a material part of this disclosure and in which—

30 Figure 1 is a fragmentary perspective view showing a portion of a building with a window and indicating the application of the invention.

Fig. 2 is a fragmentary longitudinal sectional view taken through a conventional type of window.

Fig. 3 is a plan view of the safety apron partly broken away in order to show its construction.

40 Fig. 4 is a transverse sectional view taken on line 4—4 of Fig. 3.

Fig. 5 is a perspective view showing one of the movable bracket elements.

Fig. 6 is a perspective view showing one 45 of the pair of brackets that are engaged with the window frame.

Fig. 7 is a fragmentary top plan view showing a modified rod holder.

In these drawings the numeral 10, designates an ordinary type of building in which 50 is a window having a frame 11 and sash 12 of the common type of construction.

Secured to the inner side of the frame 11, at the lower corner adjacent to the window 55 sill, is a bracket plate 14, having openings 15 to receive screws, nails, or like fastenings.

Formed with the lower portion of the bracket is a rectangular extension 16, having a corresponding rectangular opening 17 passing entirely therethrough. Engageable 60 in the rectangular opening 17 is a square shank 20 formed with a movable bracket 21, the same extending inwardly and provided with a spherical head 22 having a circular opening 23 and a winged clamp screw 65 24 by which the rod 25 may be secured in the circular opening 23 in an adjusted position.

These rods are preferably made of tubes and are adapted to fit neatly within the 70 opening 23 at their lower ends.

Engaged with the rods is a strong apron 26 made of canvas or other suitable material the same being secured to the rods by stitching along the inturned marginal edges 27. 75

In operation the fixed stationary bracket elements 16, having been secured upon the inner sides of the window frame, the movable elements are entered therein and then the rods 25 are entered into the openings 80 23, the apron 26 being extended angularly at the front of the window. In the modification shown in Fig. 7 the supporting arm 21 is formed with a semi-spherical head 30 from which extends lateral flanges 31 and 85 engageable therewith are similarly formed elements 32 formed with another semi-spherical element 23 the elements 30 and 33, having a spherical recess formed in the interior adapted to receive a ball 35 made in sections and containing an opening to receive the rod 25, the holding elements being secured by bolts 26 which, when in a clamped position, cause the sections of the ball or sphere 35 to close together clasping the rod 90 25 and obviously holding the same in any adjustment, it being possible to set the rods 25 at any desired inclination or raise or lower the same in an obvious manner.

Having thus described my invention and 100 set forth the manner of application and use, what I claim as new and desire to secure by Letters Patent, is—

1. In a safety device for windows, the combination with a pair of brackets adapted 105 to be secured on the inner sides of a window, a square base socket open at the top integral with said brackets, movable bracket elements comprising a square shank engageable in the square base socket of said fixed brackets, heads formed with said movable brackets, a pair of rods slidable in said heads,

clamp screws engageable in said heads for holding said rods in adjusted position in said heads, and an apron attached to said rods extending to opposite sides of the window and at an angle therefrom.

2. In a safety device for windows, the combination with a window frame, of a pair of brackets secured to the innermost sides adjacent to the window sill, said brackets having rectangular openings at their lower ends, movable brackets having stems engageable in the openings in said fixed brackets, said movable brackets extending toward

each other, sectional spheres engaged within said movable brackets, means for clamping said spheres in an adjusted position, a pair of rods engageable in said spheres, and a flexible textile fabric extended between said rods, said apron being firmly engaged along the length thereof and extended outwardly at an angle from the windows so as to cover the opening therethrough.

In testimony whereof I have affixed my signature.

FRANZ RICHARD BLANKENAGEL.
